UNITED STATES PATENT OFFICE

WILLIAM LILLY, OF NEW YORK, N. Y.

GASOLINE VAPORIZER

Application filed January 24, 1928. Serial No. 249,070.

This invention relates to gasoline vaporizers and has for an object a new and improved means for and method of producing a combustible mixture of gasoline vapor and air.

According to this invention a mixing chamber is provided in which there is arranged a supply of fibrous absorbent material presenting a large surface area. The fibrous material is saturated with gasoline which is held by the fibrous material through capillary attraction. The combustible mixture is obtained by directing a draft of air through and around the fibrous material. Because of the large area of contact between the air and gasoline the latter readily evaporates or volatilizes and forms an ignitable mixture with the air. This mixture may vary from one part of gasoline and nine parts of air to one part of gasoline and sixteen parts of air at 68° Baumé which proportions, as is well known, form combustible mixtures. The vaporized mixture is allowed to escape from the chamber through a suitable outlet and may be used as the fuel for cigar lighters or for internal combustion engines either for motor vehicles or motor boats or for any other purpose for which it is suitable.

A cigar or cigarette lighter embodying the invention comprises a casing having a spring actuated cover hinged thereto. Within the casing is provided a chamber in which is contained the fibrous material. A plurality of burner tubes lead from the top of the chamber and means are supplied for introducing air into the chamber under pressure. Valves for controlling the burner tubes are operable by the cover so that when the cover is closed the valves are closed and when the cover is open the valves are open. Spark producing means operable by the cover are also provided so that when the cover is operated and the valves are opened to permit a flow of gas, a spark is provided to ignite the same. The means provided for introducing a supply of air into the chamber are operable by the cover when closing so that when the cover is next opened there is an immediate flow of vaporized fuel through the burner tubes.

Other objects, novel features and advantages of this invention will be apparent from the following specification and accompanying drawings wherein,

Fig. 1 is a perspective view of a cigar lighter embodying the invention;

Fig. 2 is a vertical section through such lighter;

Fig. 3 is a section on the line 3—3 of Fig. 2;

Fig. 4 is a perspective view of a portion of the lighter;

Fig. 5 is a section substantially on the line 5—5 of Fig. 2.

The invention is disclosed specifically as embodied in a cigar lighter which comprises a casing 10 having a cover 11 pivoted thereto. A spring 12 is provided for forcing open the cover 11 when the detent 13 which normally holds the cover in closed position is released. A chamber 14 is formed within the casing by means of the partition 15 which is shown in detail in Fig. 4. One leg of the partition 15 terminates above the bottom of the casing 10 and rests upon a block 16. In the upper face of the block 16 there is provided a recess into which fits the lower end of a cylinder 17. A passageway 18 communicating with the interior of the chamber 14 leads from the recess. In the passageway 18 is provided a spring-operated ball 19 which acts as a check valve. A piston 20 is slidably arranged in the cylinder 17 and forms therewith a pump for forcing air into the chamber 15.

A plurality of apertures 21 are provided in the upper portion of the partition 15 and a slide 22 overlies these apertures. The slide is also provided with apertures 23 which in one position of the slide 22 register with the apertures 21 and in another position of the slide are out of register with the apertures 21. A lever 24 is pivotally mounted above the slide 22 and has one end engaging the same so that oscillation of the lever 24 causes reciprocation of the slide 22. The upper end of the lever 24 is formed with a yoke 25 which receives a pin 26 carried at the free end of a link 27 pivotally attached to the cover 11 at 28. The arrangement of the link is such

that when the cover 11 is closed the lever 24 is operated to move the slide 22 so that the apertures 23 are out of register with the apertures 21 and when the cover is opened to move the slide 22 to bring these apertures into register.

A plurality of tubes 29 are supported in the upper part of the casing 10 in alignment with the apertures 21 and have their lower ends engaging the slide 22. Thus when the cover 11 is open the interior of the chamber 14 is in direct communication with the tubes 27. Spark producing means 30 are supported adjacent the upper ends of the tubes 29 and the movable element thereof is connected to the pin 26 so that it is operated upon operation of the cover. Thus when the cover 11 is thrown open by the spring 12 upon release of the detent 13 the tubes 29 are put into communication with the interior of the chamber 14 and the spark producing means are operated to ignite the gas escaping from the chamber 15 through the tubes 29.

Within the chamber 14 there is provided a plurality of strips 31 of fibrous absorbent material. A material which has been found to be very satisfactory is known as southern fiber. This material after having been thoroughly washed and arranged within the chamber acts as a gasoline absorbent. This material absorbs gasoline introduced into the chamber and distributes it over a large surface. Because of the distribution of the gasoline and the large area of contact a current of air blown through and around such fiber soaked with gasoline readily evaporates or volatilizes the gasoline and forms therewith an ignitable mixture.

In the operation of this device the piston 20 is utilized to introduce air under pressure into the casing 14 so as to produce the required flow of air through the fibrous material. This is preferably done by raising the piston 20 with the cover 11 open and then closing the cover 11 at the same time forcing down the piston 20. The piston being forced down during the time that the valves are closing introduces into the chamber 14 a sufficient supply of air for the next operation of the device. Thus when the detent 13 is released and the cover 11 forced open by the spring 12 there is an immediate flow of a gaseous mixture of gasoline vapor and air through the tubes 29 which is ignited by the sparks produced by the means 30 which is operated upon the opening of the cover. The flame may be maintained if desired by pumping additional air into the chamber 14. Preferably a shield 32 is provided around the upper end of the tubes 27 as a protection against wind and draft.

Although the invention has been specifically disclosed as embodied in a cigar lighter, it is apparent that the principle of vaporizing gasoline or passing a draft of air over a

fibrous absorbent body saturated with gasoline may be utilized in many different ways and in connection with various devices depending for their operation upon a fuel comprising a mixture of gasoline vapor and air. It is to be understood that this invention is not limited to the specific embodiment disclosed but its scope is limited only by the appended claims in which the invention is presented both in its broad and one specific aspect.

75
I claim:

1. In a device of the character described, a casing having a cover pivoted thereto, a chamber containing absorbent fibrous material, means for introducing air under pressure into said chamber, a tube leading from the top of said chamber and valve means operable by said cover for controlling said tube.

80
2. In a device of the character described, a casing having a cover pivoted thereto, a chamber containing absorbent fibrous material, means for introducing air under pressure into said chamber, a tube leading from the top of said chamber, valve means operable by said cover for controlling said tube, and spark producing means adjacent one end of said tube.

85
3. In a device of the character described, a casing having a cover pivoted thereto, a chamber containing absorbent fibrous material, means for introducing air under pressure into said chamber, an unobstructed tube leading from the top of said chamber for delivering gaseous fuel and spark producing means adjacent said tube, said means being 90 rendered operative by said cover.

95
4. In a device of the character described, a casing having a cover pivoted thereto, a chamber containing absorbent fibrous material, an aperture in the top wall of said chamber, a tube in alignment therewith, a slide having an aperture adapted to be moved into and out of register with said tube and first aperture, and means for actuating said slide upon operation of said cover.

100
110
5. In a device of the character described, a casing having a cover pivoted thereto, a chamber containing absorbent fibrous material, an aperture in the top wall of said chamber, a tube in alignment therewith, a slide having an aperture adapted to be moved into and out of register with said tube and first aperture, means for actuating said slide upon operation of said cover and means for introducing air under pressure into said chamber.

115
120
125
6. In a device of the character described, a casing having a cover pivoted thereto, a chamber containing absorbent fibrous material, an aperture in the top wall of said chamber, a tube in alignment therewith, a slide having an aperture adapted to be moved into and out of register with said tube and first aperture, means for actuating said slide upon operation of said cover, and spark producing 130

means operable coincidentally with the actuation of said slide.

7. In a device of the character described, a casing having a cover pivoted thereto, a chamber containing absorbent fibrous material, an aperture in the top wall of said chamber, a tube in alignment therewith, a slide having an aperture adapted to be moved into and out of register with said tube and first aperture, means for operating said slide upon operation of said cover, means for introducing air under pressure into said chamber, and spark producing means operable coincidentally with the actuation of said slide.

15 In testimony whereof, I have signed my name to this specification.

WILLIAM LILLY.
